United States Patent Office.

JOHN F. BARTLETT, OF WINSTED, CONNECTICUT.

Letters Patent No. 90,484, dated May 25, 1869.

IMPROVEMENT IN LAMP-CHIMNEYS.

The Schedule referred to in these Letters Patent and making part of the same.

To all whom it may concern:

Be it known that I, JOHN F. BARTLETT, of Winsted, in the county of Litchfield, and State of Connecticut, have invented a new and useful Improvement in Lamp-Chimneys; and I do hereby declare that the following is a full and exact description of the same, reference being had to the accompanying drawings, and to the letters of reference marked thereon.

This invention relates to certain improvements in lamp-chimneys, whereby those portions not needed for the transmission of light are made of metal, and the glass portion constructed in sections, as will herein-after more fully appear.

In the drawings—

Figure 1 is a side elevation of my invention.

Figure 2, a perspective view of one of the glass sections.

To enable others skilled in the art to make and use my invention, I will now proceed to describe fully its construction and operation.

A represents a metal tube, which is tapering in form, and provided with the flange A', which fits over the upper part of the frame-work B.

The latter consists of the upper rim B', the vertical rods b b b, and the bottom, B², which is provided with the flange b', by which it is attached to the lamp.

The parts before mentioned are constructed of metal, and are so located as not to obstruct the light from the burner at any point where it is usually required.

Between the rods b is located the glass portion of

the invention, which consists of the annular rings or sections C, which may vary in number, as desired.

The advantages of this construction are, that the part of the chimney which is not necessary for the transmission of light, and yet indispensable to perfect combustion, is of metal, and therefore comparatively indestructible. The glass being in narrow sections, is not as liable to break by sudden changes of temperature.

The lamp can be more readily lighted, as it is only necessary to raise the upper section and bring the match in contact with the wick.

The top is easily removed, for the purpose of cleaning, and the sections, when broken, can be replaced at a small expense.

I do not claim, broadly, the idea of constructing chimneys in sections, nor the manner of holding a chimney by means of a frame, for these points I know to be old; but having thus fully described my invention,

What I claim as new, and desire to secure by Letters Patent, is—

The chimney above described, consisting substantially of the tube A, frame-work B, and glass sections C, substantially as described.

This specification signed and witnessed, this 25th day of March, 1869.

Witnesses: JOHN F. BARTLETT.
